UNITED STATES PATENT OFFICE.

GERALD DEAKIN, OF OAKLAND, CALIFORNIA, ASSIGNOR OF ONE-HALF TO McMEEN & MILLER, OF CHICAGO, ILLINOIS, A COPARTNERSHIP COMPOSED OF SAMUEL G. McMEEN AND KEMPSTER B. MILLER.

INTERCOMMUNICATING TELEPHONE SYSTEM.

1,159,188.

Specification of Letters Patent.

Patented Nov. 2, 1915.

Application filed August 12, 1909. Serial No. 512,526.

To all whom it may concern:

Be it known that I, GERALD DEAKIN, a citizen of the United States of America, and a resident of Oakland, county of Alameda, 5 and State of California, have invented a new and useful Improvement in Intercommunicating Telephone Systems, of which the following is a specification.

My invention pertains to intercommunicating private branch exchange systems.

Specifically it is shown pertaining to such systems used in connection with automatic central offices and connected with the central office by a trunk or a series of trunks.

By intercommunicating exchange is meant an exchange at which each subscriber has direct access to all the telephone lines of the exchange and operates a switching device at his station to connect his telephone set with any desired one of the lines. When such an exchange includes as one of its lines the conductors of a trunk leading to a public service exchange, the intercommunicating system becomes a branch exchange of the 20 public telephone system. With such an arrangement, any station ordinarily would have the ability to connect its telephone with the conductors of the trunk leading to the public central office. This would permit the 25 interruption of a conversation by any second station of the branch exchange which might attempt to forward a call over a busy trunk.

My invention has for its object the provision of equipment and a system of operation 30 by which a busy trunk circuit may be guarded at the private branch exchange from all interruption by other stations which may attempt to forward a call over that trunk.

In the system of my invention I provide 35 also equipment such that, on an attempted outgoing call from an intercommunicating private branch station, upon the trunk already being used on an outgoing connection, the calling subscriber will not be permitted to connect his telephone set to the trunk conductors, and furthermore his ringing buzzer will be operated, thereby indicating to him audibly that the trunk with 40 which connection is attempted is busy. If, however, the trunk is busy on an incoming call, a second station under some circumstances will be permitted to come in upon the trunk, this being necessary by the gen-

eral plan of operating private branch exchanges, whereby all calls incoming are answered by an attendant at a predetermined station and the identity of the person desired for conversation is ascertained, that person then being notified by any available means 55 and then connecting himself to the trunk line to respond to the incoming call. This requires that on an incoming call a second station may be permitted to connect its telephone set to the trunk while the first station, 60 or attendant's station, still is upon the trunk for the purpose of supervising the call until the beginning of conversation.

I provide means whereby after the desired party is obtained with an incoming call, he 70 may arbitrarily place the guarding condition upon the trunk, preventing access of other stations who might inadvertently interrupt the conversation.

In this class of private exchange it is customary at times for the attendant at the call-receiving station to disconnect his telephone from the trunk after answering and ascertaining the station desired and then to notify the desired station over one of the local intercommunicating lines. In such practice, during the interval between the release of the trunk at the receiving station and the picking up of the trunk at the desired station the trunk line to the central office will 80 be open with possible consequent undesirable operation of the central office relays, signals or other apparatus designed to be controlled by the called subscriber's bridge. This operation in the case of a manual exchange is very objectionable and might be 85 equally so in automatic exchanges. I provide mechanism whereby a bridge circuit is maintained at the receiving station across the trunk of an incoming call until the 90 trunk is picked up by the desired station, at which time the bridge at the receiving station is removed automatically and the trunk is left under full control of the desired station.

I provide further an automatic signaling means whereby any local station in attempting to call any other local station is notified in case the station called is already in use. This differentiates from the ordinary busy 105 test by providing for a signal which becomes active dependently upon the busy or idle condition of the telephone of the station

rather than upon the busy or idle condition of the line over which that station may be called. Thus, if station A calls station B, A will use B's line, in so doing leaving A's line idle although A's station is busy on B's line. Station C desiring to call station B will receive the busy test as ordinarily provided. Station C desiring to call station A would not receive a busy test as ordinarily provided because the line to station A is not busy and station C might ring indefinitely upon station A, annoying the person at that station by a ringing upon his bell to which he is unable to respond. In my improved system, I provide a signal whereby station C is notified that station A is busy, and the telephone user at station C then may conduct himself accordingly.

In the drawings which accompany and form a part of this specification, Fig. 1 shows circuits of the private branch exchange system comprising three local lines and one trunk line. Fig. 2 shows the substation circuits of a station other than the receiving station, and Fig. 3 shows the substation circuits of the receiving station; the receiving station differs from the other stations in that it is called upon to perform different functions.

The central office circuits are not shown, as it is thought that the system may be understood completely without confusing the drawings by the addition of matter related only indirectly to the subject matter of my invention.

The keys of Fig. 1 are locking keys and preferably are of the mutually locking type in which the depression of any key results not only in the locking of that key in its depressed position, but also in the unlocking and consequent restoration of any other key which may have been locked in its depressed position at that time. In addition to the switching contacts whereby the substation telephone may be connected to the selected line, each key is provided with additional contacts for the signaling and guarding features of my invention.

Referring to key 3^Y , the contacts $3'$ and $3''$ are adapted to connect the telephone set to the line extending to station Z, and the contact 3^y is a ringing contact operated to connect with the line extending to station Z only when the key 3^Y is fully depressed, and key 3^Y then returning to an intermediate position in which 3^y is open and $3' 3''$ are closed, that being the locking position of depression of the key.

The substation equipments of Figs. 2 and 3 are of the type used by the Automatic Electric Company and are described in United States Patent No. 866,639, September 24, 1907, to E. D. Fales, to which a few additional switching springs have been added, the operation of which will be under-

stood readily. Fig. 2 represents the substation equipment of a station such as Z, Y, etc., and is considered to be connected to the correspondingly lettered terminals of a station as Z, Fig. 1. Fig. 3 represents an attendant's equipment or receiving station such as X and is considered to be connected to the correspondingly lettered terminals as shown at X, Fig. 1.

Upon an outgoing call from the private branch exchange, the patron, say at station Y, depresses his trunk key YT Fig. 1 and forwards the call by operating his dial Fig. 2, the signaling currents finding direct conducting path through the contacts of the relay 9, the bridge of the ringer 10 being opened by the condenser 11, to the right as viewed in Fig. 1 along the heavy lines to the central office apparatus.

The signaling circuits are as follows: For the vertical impulse signals the circuit is from grounded terminal G^1 (Fig. 2), thence to and through terminal G^2 , the pair of contact springs shown immediately above the signal transmitter, which springs are closed as soon as the dial is moved from its normal position, the middle spring of the impulse springs, thence, when the signal transmitter is operated, to the upper or vertical impulse spring, the terminals V^2 , V^1 , lefthand contacts of relay 19, terminal V, conductor V at station Y (Fig. 1), to and through the contacts of key YT, the upper heavy line or vertical side of the trunk to the central office, thence through the vertical stepping means at the central office to the ungrounded pole of the central office battery.

The circuit for the rotary impulse is as follows: from ground (Fig. 2), through terminals G^1 , G^2 , to and through the pair of contact springs immediately above the signal transmitter, thence to the middle impulse spring, lower impulse spring to the terminals R^2 , R^1 , through the right hand armature and contact of relay 19 to terminal R, thence to conductor R, station Y (Fig. 1), to and through the lower pair of contact springs of key YT, to the lower heavy line or rotary side of the trunk line, the left hand contacts of relay 9, to the rotary side of the trunk line extending to the central office, thence through the rotary stepping means at the central office to the ungrounded pole of the central office battery. The operation of the dial of the calling station whose equipment is shown in Fig. 2 changes the position of the switching element 12, the switch element 12 then remaining in contact with its right hand element until the depression of the hook lever. This offers a path from the negative side of the ringing battery RB of Fig. 2 through terminals B^1 — B^2 , conductors 13, 14, switch element 12, conductors 15 to terminal P of

130

Fig. 2, thence to terminal P of the station Y in Fig. 1 through a contact of key YT to conductor 16 or guard conductor of the trunk, thence through relay 25 to plus side 5 of battery RB, operating relay 25 and opening the ringer bridge of the trunk.

Should station Z attempt to call upon the trunk, his first act would be to depress his key ZT. This would give a circuit beginning at the negative side of ringing battery and extending through terminals B¹—B² of station Y thence through 13, 14, 12, 15, P, YT, 16, to station Z, thence through key ZT, terminal P of station Z, conductor 15, switch element 12, and its left hand contact element, conductor 17 of station Z to and through closed contact of hook switch when elevated, conductor 18, helix of relay 19, to positive side of ringing battery which is common to 20 all stations, thus energizing relay 19 and accomplishing two results. The first result is the breaking of the conducting paths between VI—V, and R¹—R, the terminals V and R being connected to the trunk conductors at the key ZT, and the telephone set being removed therefrom by the operation of the relay 19. The further result is the closing of a local circuit extending from negative side of ringing battery RB to terminal 30 B¹ to and through armature 19' and its contact, through buzzer 20 and to terminal B³ which is the positive terminal of RB. This gives an audible signal on the buzzer 20 as long as the switchhook is elevated and the 35 key ZT depressed announcing to the attempting patron that the trunk line is busy. It is not the intention of the system of my invention to lock out the private branch station from the trunk conductors positively, 40 but only to protect the user of the trunk conductors against unintentional interruption. If the patron at station Z, learning that the trunk line is busy, still desires to connect his telephone with the trunk line, he may do so 45 by giving one pull upon his transmitting dial, thereby operating his switch element 12, removing the relay 19 from its connection with the wire 16, the relay 19 thereby releasing its armature and placing the telephone set of station Z in connection with the trunk conductors.

On an incoming connection where the private branch exchange patron is the called party to the conversation, the dial at the private branch exchange is not operated and switch element 12 is not shifted. For this reason the guarding condition is not placed upon the guard wire 16, and any number of stations may come upon the line intentionally or otherwise. This is necessary in order that the desired party to an incoming call may be permitted to have access to the trunk to answer the call, but the guarding condition may be placed upon the guard wire 16 65 at any time by any station merely by giving

ing a single pull to the dial, thus shifting the switch element 12.

When a local station as station Y calls another local station as station Z, the call is effected by depressing the key 3^Y, fully to 70 close its contact 3^Y and then releasing to its locking or intermediate position. During the complete depression of the key 3^Y, assuming that station Z is in idleness, a circuit will be formed extending from the plus side 75 of the common ringing battery RB Fig. 2 over the bus wire of the system to terminal B³, thence through ringing buzzer 20 to terminal RB of Fig. 2, which is connected to conductor RB of Fig. 1 and to contact 3^Y of 80 key 3^Y, then to one of the wires of the line upon which it is desired to ring and over that wire to station Z, thence over wire C Fig. 1 at station Z to terminal C of Fig. 2 through the vibrating call bell 22 of station Z 85 through terminals C¹—C² and closed contact pair of hook switch, terminals B²—B¹ and bus wire to minus side of the ringing battery. Current flowing over this circuit will operate the call bell 22 of station Z 90 and the ringing buzzer 20 of station Y, announcing to station Y that the call bell at station Z is being actuated. If, however, the hook at station Z were elevated, the contact of the hook switch included in the circuit 95 would be broken and neither the call bell of the desired station nor the buzzer of the originating station would be actuated, thus giving a negative signal to the originating station indicating the busy condition of the 100 desired station. The called subscriber at Z answers by depressing the key corresponding to his own station. In the receiving station the hook switch contact of the above circuit is replaced by the conductor 24. An 105 exception is made at the receiving station, its circuit being so arranged as to permit its bell to be rung at any time in order that the receiving station may be called while handling incoming calls or other business. 110

In incoming calls from the central office, the call is answered regularly at the receiving station, the ringer 10 being located at that station, and the ringing current from the central office coming in from the right along the heavy lines as viewed in Fig. 1 and passing through the bridge at the receiving station formed by the armature of relay 25, bell 10, armature of relay 9 and condenser 11, thus causing the operation of the bell 10. 115 The attendant at the receiving station answers by depressing the proper trunk button and learns the identity of the station desired. The act of answering by depression of the key XT places the attendant's telephone across the telephone pair in series with the windings of relay 9, thus energizing that relay and closing a bridge path across the pair composed of one winding of the relay 9, an armature and contact of the 120 125 130

same relay, and the ringer 10, the relay winding involved being shunted by a condenser 23. The circuits established when the attendant operates the key XT are as follows: from the ungrounded pole of the central office battery over the upper or vertical side of the trunk line (Fig. 1), through the contacts of key XT, thence to conductor V, terminal V (Fig. 3), left hand armature 10 and contact of relay 19, terminal V¹—V², to and through upper pair of hook-switch contacts of the subscriber's station instrument (which contacts are closed when the receiver is removed from the hook), thence through 15 the transmitter, primary winding of the induction coil, terminals R², R¹, right hand armature and contact of relay 19 to terminal R, thence by conductor R (Fig. 1, station X) to lower set of contacts of key XT, thence to 20 and through the two windings of relay 9 in parallel to the lower or rotary side of the trunk line, thence over this trunk conductor to the grounded pole of the central office battery.

25 The circuit just described includes the windings of relay 9 in parallel, which will cause this relay to operate. The circuit conditions after the operation of relay 9 are as follows: The circuit, as previously described, 30 remains the same to the lower set of contacts of the key XT (Fig. 1). It then extends to and through right hand winding of relay 9, thence by the rotary trunk conductor to the central office. The operation of relay 9 establishes a bridge path across the vertical and rotary conductors of the trunk line as follows: from the vertical side of the trunk line to and through contact and armature 35 of relay 25, ringer 10, right hand armature 40 and inner contact of relay 9, right hand winding of relay 9 to the rotary side of the trunk line.

The attendant now may leave the trunk to 45 call the local station desired, the signals or relays at the central office being held in proper condition of control by the trunk bridge composed of the relay winding and the ringer 10. The attendant at the receiving station notifies the party at the desired 50 station, and the desired party now depresses the proper trunk button at his station Y or Z. This act, in addition to picking up the trunk, automatically removes the bridge at the receiving station since the current taken 55 by the desired station at key YT or ZT is taken through both of the differential windings of relay 9 in series, thus demagnetizing the relay and releasing its armature and short circuiting the windings. The central 60 office devices are now fully under the control of the bridge at the desired station and he may place a guard upon the trunk by pulling his dial once.

65 The attendant is notified that the desired patron has picked up the trunk in the fol-

lowing manner: So long as he has not picked up the trunk, the relay 9 will remain energized and a path will extend from the minus side of ringing battery RB, see Fig. 1, through armature and contact of relay 9, 70 thence through resistance 9', conductor T¹ to terminal T¹ of Fig. 3, terminal C² and to and upon switch spring of the hook switch of the receiving telephone set. If the attendant hangs up the receiver before the desired party picks up the trunk, this path will be extended farther through the hook switch and through terminals B² and RB, 75 and ringing buzzer 20, to terminal B³, completing the circuit, and operating the buzzer 80 20, thus announcing to the attendant that the trunk has not been picked up by the desired party. This does not operate the relay 25 to break the bridge of the ringer 10.

The horizontal arrow to the left of the resistance 9' is a contact on a relay 9 associated with another trunk when more than one trunk is employed.

I claim—

1. In a telephone system, a pair of speech 90 current conductors, a guard wire associated therewith, a telephone set, an audible signal device, a relay therefor, a source of current; means in said telephone set for closing a path from said guard wire through said relay to one terminal of said source of current upon the initiation of a call, and further means for interrupting said path and for substituting therefor a path from said guard wire to the other side of said source of current and not including said relay. 95

2. In a telephone system, a pair of speech current conductors, a guard wire associated therewith, a telephone set, an audible signal device, a relay therefor, a source of current and means in said telephone set for closing a path from said guard wire through said relay to one terminal of said source of current upon the initiation of a call; further means for interrupting said path and for substituting therefor a path from said guard wire to the other side of said source of current and not including said relay, said further means being associated with automatic call sending devices of the telephone set and 100 operated incidentally to the prosecution of the call. 105

3. In a telephone system, a pair of speech current conductors, a guard wire associated therewith, a telephone set, a telephone disabling relay; a source of current; means in said telephone set for closing a path from said guard wire through said telephone disabling relay to one terminal of said source of current upon the initiation of a call; and further means for interrupting said path and for substituting therefor a path from said guard wire to the other side of said source of current and not including said telephone disabling relay. 110 120 125 130

4. In a telephone system, a pair of speech current conductors, a guard wire associated therewith, an automatic telephone set, a relay for disconnecting said telephone set from said pair; a source of current; means in said telephone set for closing a path from said guard wire through said relay to one terminal of said source of current upon the initiation of a call; further means for interrupting said path and for substituting therefor a path to the other terminal of said source of current and not including said relay, said further means being associated with the automatic call sending devices of the telephone set and operated incidentally to the prosecution of the call. 70
5. In a telephone system, a pair of speech current conductors, a guard wire associated with said pair, a telephone set, a busy test battery normally not in operative relation to said guard wire, an audible signal controlling relay, a hookswitch contact for placing said relay between said guard wire and one side of said busy test battery, thereby forming a busy test path, and a switch for removing said test path and for connecting said guard wire to the other terminal of said battery. 75
6. In a telephone system, a pair of speech current conductors, a guard wire associated with said pair, a telephone set, a busy test battery normally not in operative relation to said guard wire, automatic means for placing a telephone disabling relay between said guard wire and one side of said busy test battery to protect against interference with other telephone sets. 80
7. In a telephone system, a pair of speech current conductors, a guard wire associated with said pair, a telephone set, a relay for disconnecting said telephone set from said pair; a busy test battery normally not in operative relation to said guard wire, automatic means for connecting said relay between said guard wire and one side of said busy test battery to protect against interference with other telephone sets, and manually operated means for disrupting said connection. 85
8. In a telephone system, a pair of speech current conductors, a guard wire associated with said pair, an automatic telephone set, a relay for disconnecting said telephone set from its line conductors, a busy test battery normally disconnected from said guard wire, hook switch contacts for connecting said relay between said guard wire and one side of said busy test battery to protect against interference with other telephone sets, and a switch for disrupting said connection and for connecting said guard wire to the other side of said battery, said switch being operated by a movement of the automatic calling devices of the telephone set. 90
9. In a telephone system, a relay having two windings; a pair of speech current conductors in one of which the windings of said relay are included, serially and differentially; contacts on said relay and short-circuiting said windings when in normal position; contacts on said relay and connecting one of said windings in a path across said pair when in actuated position; a circuit controlled by a receiving telephone set and passing current through both of said windings inductively to actuate said relay initially; and a circuit controlled by another telephone set for passing current through both of said windings differentially to release said relay. 95
10. In a telephone system, a relay having two windings; a pair of speech current conductors in one of which the windings of said relay are included, serially and differentially; contacts on said relay and connecting one of said windings in a path across said pair when in actuated position; a circuit controlled by a receiving telephone set and actuating said relay initially; and a circuit controlled by another telephone set for passing current through both of said windings differentially to release said relay. 100
11. In a telephone system, a relay having two windings; a pair of speech current conductors in one of which the windings of said relay are included, serially and differentially; contacts on said relay and short-circuiting said windings when in normal position; contacts on said relay and connecting one of said windings in a path across said pair when in actuated position; a circuit controlled by a receiving telephone set and actuating said relay initially, and a circuit controlled by another telephone set and releasing said relay. 105
12. In a telephone system, a plurality of automatic telephone instruments, a trunk circuit extending from said instruments to an automatic central office, a plurality of local intercommunicating circuits between said instruments, means at each instrument for connecting with said trunk or local intercommunicating circuits, and an automatic guard for said trunk circuit made operative when any one of said instruments is connected therewith. 110
13. In a telephone system, a plurality of automatic telephone instruments, a plurality of trunk circuits extending from said instruments to an automatic central office, a plurality of local intercommunicating circuits between said instruments, means at each instrument for selectively connecting with either of said trunk or local circuits, and an automatic guard for each of said trunk circuits made operative when any one of said instruments is connected therewith. 115
14. In a telephone system, a plurality of telephone instruments, a trunk circuit ex- 120
- 125
- 130

tending from said instruments to an automatic central office, automatic sending devices associated with each of said instruments for establishing connection over said 5 trunk line through said central office, a plurality of local circuits for intercommunicating between said instruments, means at each instrument for connecting it with said trunk or local intercommunicating circuits, and an 10 automatic guard for said trunk circuit made effective when one of said instruments is connected to said trunk circuit.

15. In a telephone system, a plurality of telephone instruments, a trunk circuit extending from said instruments to an automatic central office, automatic transmitting devices for each of said instruments, a plu-

rality of local circuits for intercommunicating between said instruments, means at each instrument for connecting it with said trunk 20 or local intercommunicating circuits, and means whereby the user of one of said instruments who has responded to a call over said trunk may arbitrarily place a guarding condition upon said trunk to prevent access 25 of other stations to that trunk.

Signed by me at San Francisco, county of San Francisco and State of California, in the presence of two witnesses.

GERALD DEAKIN.
